UNITED STATES PATENT OFFICE.

FRANCIS H. RICHARDS, OF HARTFORD, CONNECTICUT.

ADJUSTABLE TOOL-SUPPORT.

No. 902,169.

Specification of Letters Patent.

Patented Oct. 27, 1908.

Application filed December 16, 1902. Serial No. 135,373.

To all whom it may concern:

Be it known that I, FRANCIS H. RICHARDS, a citizen of the United States, residing at Hartford, in the county of Hartford and State of Connecticut, have invented certain new and useful Improvements in Adjustable Tool-Supports, of which the following is a specification.

My present invention pertains to tool supports for machines employing rigidly secured tools and relates more particularly to a tool post or tool head construction wherein longitudinal and lateral adjustment of the tool is provided for, as well as means for rigidly securing the tool in its adjusted position, and comprehends means for longitudinal adjustment independently of the lateral adjustment and vice versa, and the combination of a tool head having the above-named properties with a novel form of tool hereinafter described.

Some of the objects of my invention are to provide a tool post or tool head of simple and effective construction providing novel means for the longitudinal adjustment of the tool and for the lateral adjustment of the tool without disturbing said longitudinal adjustment and vice versa, together with positive means for securing the tool in its adjusted position.

I have illustrated my invention embodied in one form of tool head in the accompanying drawings, in which like reference characters indicate like parts throughout the several views.

Figure 1 is a perspective of the upper portion of a tool head embodying my present invention; Fig. 2 is a vertical cross-section through the center of the tool; Fig. 3 is a bottom view in perspective of the tool clamp showing the adjusting screw removed, and Figs. 4 and 5 are a side elevation and a plan of the tool respectively.

Referring to the drawings the base portion 2 of the tool head is provided with a dove tail tenon 3 upon its upper surface and running across said upper surface. A tool carrying portion 4 of the tool head is provided with a dove tail mortise in its under surface and is adapted to be slidably mounted upon the base portion 2, the dove tail tenon 3 engaging the dove tail mortise in the under surface of the tool carrying portion 4. The tool carrying portion 4 is slit lengthwise of

the dove tail mortise therein at 5, said slit at 5 being of such a depth that when a screw 6, which has a shoulder 7 adapted to abut the tool carrying portion 4 and threaded into the is inserted loosely through one part of said tool carrying portion 4 and threaded into the other part of said tool carrying portion 4 beyond the said slit is tightened, the two portions of the tool carrying portion 4 upon either side of the slit will be brought together, the spring of the metal permitting this. The slit 5 is preferably made from the interior of the dove tail mortise in the tool carrying portion adjacent one inclined wall of said mortise, and the screw 6 is inserted from the side of the tool carrying portion nearest said slit. The tool carrying portion 4 is machined to fit the base portion 2 accurately, allowing enough for the sliding of the tool carrying portion 4 upon said base portion 2. When the dove tail mortise in the tool carrying portion 4 is machined it may be made very close to the same size as the tenon 3, or perhaps a trifle smaller, as the spring of the parts of the tool carrying portion 4 at either side of the slit at 5 will allow of said tool carrying portion 4 being forced upon the base portion 3 and the sliding of said tool carrying portion 4 upon said base portion 2.

The tool carrying portion 4 is made flat upon its upper surface with a shoulder 8 along its rear side extending somewhat above the said upper surface. A channel 9 is provided transversely of the tool carrying portion 4 in the upper surface thereof in which, the tool 10 is seated. The upper surface of the tool 10 is raised slightly above the upper surface of the tool carrying portion 4 and one end of the clamp 11 is adapted to rest upon a suitable bearing portion of the upper surface of the tool 10, the other end of said clamp 11 having a shoulder 12 upon its under surface adapted to contact the upper surface of the tool carrying portion 4. A screw 13 has a shoulder 14 which abuts the upper surface of the clamp 11. Said screw 13 passes loosely through the clamp 11 and is threaded into the tool carrying portion 4. The screw 13 passes through the clamp 11 between the shoulder 12 and the tool 10. It will be seen that if the screw 13 is tightened that end of the clamp 11 resting upon the tool 10 will

secure the tool 10 in its journal 9. The upper surface of the tool 10 is provided with a female thread somewhat in the form of a rack, and a screw 15 threaded its entire length is placed in a cylindrical cavity 16 runs parallelly of the tool 10 and is intercepted by the under surface of the clamp 11 opening downward upon the upper surface of the tool 10. The screw 15 is inserted from the side of the clamp 11 and its threads extending below the under surface of the clamp engage the female threads or rack upon the upper surface of the tool 10. The screw 15 abuts the inner end of the cylindrical cavity 16 and it will be seen that when the screw 13 is slightly loosened a fine longitudinal adjustment of the tool 10, may be had by operating the screw 15. When the proper adjustment is made the screw 13 is tightened. The lateral adjustment of the tool is accomplished by sliding the tool carrying portion 4 upon the base portion 2 and securing it by drawing in the sides of the dove tail mortise in the tool carrying portion 4 upon the dove tail tenon by means of the screw 6.

It is obvious that many changes in form and arrangement of the several parts of this device may be made without departing from the spirit of my invention.

Having thus described my invention, I claim—

1. The combination with a tool support having a tool receiving recess, of a tool 35 adapted to move longitudinally therein and having a worm rack on its upper face, a tool holder having a portion bearing on said support, a screw mounted in said holder and interposed between the same and said tool, 40 and means for locking said holder to said support.

2. The combination with a tool support having a tool receiving recess and a bearing portion, of a tool mounted in said recess for 45 longitudinal movement and having a worm rack, a holder for said tool comprising a member having a bearing portion at a distance from said recess on said support, a screw mounted in said holder and interposed between the same and the tool and engaging said rack, and means for clamping the holder upon said screw and bearing portion of the support.

Signed at Nos. 9-15 Murray St., New York, N. Y., this 18th day of December, 1902.

FRANCIS H. RICHARDS.
